UNITED STATES PATENT OFFICE.

WOLF SCHEINMAN, OF BALTIMORE, MARYLAND, ASSIGNOR OF ONE-THIRD TO LOUIS S. GOLDBLOOM AND ONE-THIRD TO JOSEPH H. BEARMAN, BOTH OF BALTIMORE, MARYLAND.

GARMENT HANGER.

Application filed January 5, 1924. Serial No. 684,532.

To all whom it may concern:

Be it known that I, WOLF SCHEINMAN, a citizen of the United States, residing at Baltimore, in the State of Maryland, have 5 invented certain new and useful Improvements in Garment Hangers; and I do hereby declare the following to be a full, clear, and exact description of the invention, such as will enable others skilled in the art to which

10 it appertains to make and use the same.

My invention relates to garment hangers.

Among the objects of my invention are:—

To provide a garment hanger so constructed and arranged that garments are 15 efficiently retained thereon.

To provide a garment hanger so constructed and arranged that it may be used for garments of various sizes and yet such garments are efficiently retained thereon.

20 My invention has special reference to garment hangers of the hanging type in which the arm supporting the garments is curved. This type of hanger is well suited for the displaying of garments inasmuch as the

25 curved supporting arm serves to retain the shape of the garments, but it has an inherent disadvantage in that certain types of garments, such as those made of silk, readily slip therefrom.

30 Garment hangers whose ends are turned upwardly have been provided in order to overcome this difficulty, but the upwardly turned ends tend to ruin the shape of the garment.

35 My invention comprehends the best features of these two types of hangers in that it combines the curved supporting arm with means to prevent the garment from slipping.

These and further objects of my invention 40 will be set forth in the following specification, reference being had to the accompanying drawings, and the novel means by which said objects are effectuated will be definitely pointed out in the claims.

45 In the drawings:—

Figure 1 is an elevation of my improved garment hanger.

Fig. 2 is a view looking in the direction of the arrow 2 in Fig. 1.

50 In the drawings:—

10 represents a curved garment supporting

arm provided with the usual hook 11 for suspending the hanger in any convenient location. The arm 10 is further provided with a slot 12 on each side of the hook 11. 55

A threaded pin 13 provided with a head 14 for coacting with the under surface 18^a of the arm 10 slides freely within the slot 12, and a thumb nut 15 is threaded on said pin. 60

The nut 15 may be made in any desired shape, but is preferably formed with the enlarged head 16 as shown in Fig. 1 in order to better retain the garment on the hanger and is further provided with a portion 17 65 for co-acting with the top surface 18 of the arm 10.

The garment having been placed on the arm 10, the nuts 15 are unscrewed sufficiently to permit the pins 13 to be moved along 70 the slots 12 until said nuts contact with the garment, after which the nuts 15 are screwed tight on the surface 18, thus locking the pins 13 and the nuts 15 in position.

It will be seen, therefore, that my improved hanger comprehends not only a curved arm which maintains the shape of the garment, but is also provided with means for retaining said garment in place. 75

While I have shown one preferred form 80 of my invention, it is to be understood that the disclosure is for the purpose of illustration only and in nowise to limit my invention to the exact elements and combinations thereof shown, for many changes may 85 be made in the same without departing from the spirit of my invention.

I claim:—

In a garment hanger, the combination with 90 an arm provided with suspending means, and a slot extending vertically through said arm on each side of said means, of means for retaining garments of various sizes in position on said arm, consisting of a pin freely 95 slidable in each of said slots and extending above said arm.

In testimony whereof, I affix my signature.

WOLF SCHEINMAN.
